UNITED STATES PATENT OFFICE:

FRANK E. WILSON, OF CLEVELAND, OHIO, ASSIGNOR TO THE WILSON FASTENER COMPANY, OF CLEVELAND, OHIO, A CORPORATION OF OHIO.

GARTER BUCKLE.

Application filed October 3, 1925. Serial No. 60,138.

This invention is concerned with clasps or buckles and has for its general object the provision of a quickly attachable or detachable buckle adaptable for the joining of the 5 ends of elastic bands.

More specifically, my invention is directed to the provision of a double clamping buckle which, while being neat in appearance, incorporates structural features affording a 10 ready insertion for the ragged edges of thick or shirred elastic bands beneath the buckle clasps.

A further object of my invention is the provision of a double clasp buckle for elastic 15 bands which will afford long leverage on the clamping members but which may be arranged in a compact manner convenient and comfortable to the wearer.

Other objects of my invention will become 20 apparent in the following description referring to the accompanying drawings illustrating a preferred embodiment thereof. The essential characteristics are summarized in the claims.

Fig. 1 of the drawings shows the adaptation 25 of my buckle to the joining of the ends of a stylish elastic band; Fig. 2 is a front view of the buckle detached from the band; Fig. 3 is a perspective view showing the back face 30 of the buckle; Fig. 4 is an end view of the buckle with the clasp or clamping members in a closed or clamping position; Fig. 5 is a similar view to Fig. 4 with the clamping members swung to open position, thus conditioning the buckle for the reception of the 35 band ends; Fig. 6 is a rear view of the buckle with the clamping members swung to an extreme outward position; Fig. 7 is a cross-sectional view taken substantially along the line 7-7 of Fig. 2, and Fig. 8 is a perspective view of the under side of one of the clamping members.

My invention contemplates a double clamping buckle structure which may be applied to the free ends of sleeve or garter bands in a very simple manner, and particularly, bands of the prevailing shirred style wherein the elastic is completely covered by outer layers of tucked or gathered material. Such bands are considerably thicker and more irregular than the usual flat elastic band heretofore used, and to obtain a buckle which will permit a quick insertion of the jagged thick ends of such a band, and effectively hold them 55 and at the same time shall be comfortable and

neat in appearance is a problem which I aim to solve by this invention.

In accomplishing my object I provide a body 10 and two clamping members 11 and 12 hinged thereto. I construct the body of 60 the buckle and the clamping members there- of in a bowed or concave relation so that when the clamping members are swung to an open position, a maximum opening is presented to the buckle structure at each side thereof 65 for the reception of the band ends. This maximum opening presentation is shown clearly in Fig. 5 wherein the front or body member 10 of the buckle is formed in bowed fashion and the jaw portions of the clamping 70 members 11 and 12 are formed to be bowed in an opposite direction.

The clamping members are preferably 75 duplicates of each other and as shown in Fig. 8 may each comprise a stamping having a handle portion as 11 and jaw portion 20 pro- 80 vided with a serrated edge and pivot lugs 18 at its ends. The handle extends laterally from a portion of the jaw adjacent one end only. The body 10 may have the front there- of plain or it may be scrolled or ornamented in any suitable manner, and it may be pro- 85 vided at the top and bottom with flanges 14 which are dented at the ends thereof as shown at 15 and 16 to receive pivot lugs 18 formed 85 on the clamping member's 11 and 12. This denting provides cups for the pivot lugs instead of holes through which the lugs ex- 90 tend and thus eliminates the possibility of the wearer's garments catching on these lugs. 90

The side edges of the member 10 and the serrated outline of the clamping members are preferably of such shape that when the clamps are swung to closed position, as shown in Fig. 3, the teeth thereof will overswing 105 or lie slightly outside of the edges 24 of the body member 10, as shown in Fig. 7. This relationship of the teeth 21 to the edges 24 causes the greatest impingement of the teeth into the fabric just before the clamping mem- 100 ber comes to closed position, thus throwing an extra stress on the device in opening and insuring a binding action of the teeth upon the band end when the buckle is closed.

The arms or lever portions 11^a and 12^a of the clamping members are so dimensioned that the ends thereof will extend slightly be- 105 yond the sides of the buckle structure. These ends are turned inwardly to insure comfort to the wearer of the elastic band and the back 110

portions 30 of the members 11 and 12 are indented a sufficient amount to obtain a substantially flat surface on the back of the buckle when the clamps are closed. This indentation may be in depth substantially equal to the thickness of the metal from which the clamping members are made, as shown in Fig. 3, so that when the clamping members are closed, the lever portions 11^a and 12^a respectively overlie the clamping members 12 and 11. Hence each lever portion tends to react on the other clamping member and also prevents the opening of the buckle when the elastic band and buckle are in position on the wearer.

From the foregoing description of my invention it will be seen that a buckle structure such as I herein set forth may have the exposed contour thereof of an artistic shape and that such shape is advantageous in that a maximum clearance may be presented between the body of the buckle and the jaws of the clamping members. It will also be apparent that the clamping members may be of a maximum over-all dimension to afford a ready manipulation thereof in both the closing and opening of the buckle. These clamping members may be constructed in such manner as to present a substantially flat back to the buckle with all metallic edges of the buckle subdued to prevent irritation to the wearer. The relationship of the clamping contour to the body contour is such that the elastic band when once clamped by the clamping members, cannot cause an opening movement of the clamping members by reason of the overhang thereof relative to the body edges but on the other hand tends to more firmly clamp the bulky material comprising the elastic band.

Having thus described my invention, I claim:

1. In a buckle, the combination of a body and a pair of clamping members each clamping member having a back flange from a portion of which adjacent one end only extends a lever arm overhanging the other clamping member, each back flange being indented at the place of the overlapping of the lever portions of the clamping members.

2. In a buckle, the combination of a bow shaped body having a pair of concavely formed edges, a pair of clamping members pivotally connected to the body, said clamping members having convexly formed edges conforming to the contour and the concavity of the body edges when in a clamping position.

3. In a buckle of the character described,

the combination of a body member having parallel flanges formed along two edges thereof, said body member having two other edges concavely formed, a pair of clamping members pivotally connected to the flanges of the body member, said clamping members having jaw flanges conforming to the contour of the concave edges of the body when closed.

4. In a buckle, the combination of a buckle body having a concave edge and a clamping member pivotally connected to the body and formed with a surface concave in an opposite direction relative to the body concavity when the clamping member is in an open position, said clamping member having a clamping edge thereof convexly formed corresponding to the concavity of the body edge.

5. In a buckle of the character described, the combination of a body member having parallel flanges formed along two opposite edges thereof, said body member having two other opposite edges concavely formed, a pair of clamping members pivotally connected to the flanges of the body member, and each having an arm adapted to overlap the other, said clamping members having jaws the outer surface of which is concave and the edge of which is convex to conform to the contour of the body when closed.

6. In a buckle, the combination of a pair of clamping members, said clamping members having jaws the outer surface of which are concavely formed and a bowed body member to which the clamping members are pivotally attached, the gripping edges of the jaws being formed to overhang the edges of the body member by a distance considerably less than the thickness of the material adapted to be clasped by the buckle.

7. In a buckle of the character described, the combination of a flanged body member, having concave edges extending between the flanges, and a pair of clamping members pivotally attached to the flanges, each of said clamping members having a clamping jaw thereon provided with a surface concaved toward the body when the buckle is open, the edge of said jaw being convex and adapted to overhang the adjacent concave edge on the body member and be substantially parallel therewith when the buckle is closed and each clamping member having an arm adjacent one end and adapted to overhang the other clamping member.

In testimony whereof, I hereunto affix my signature.

FRANK E. WILSON.
